US00D630940S

(12) **United States Design Patent**
Shapiro et al.

(10) **Patent No.:** US D630,940 S
(45) **Date of Patent:** ** *Jan. 18, 2011

(54) **CONTAINER ASSEMBLY**

(75) Inventors: **Catherine M. Shapiro**, Omaha, NE (US); **Jess C. Sweeney**, Omaha, NE (US); **Brian M. Degner**, Omaha, NE (US); **Darin Charles Koestring**, Evansville, IL (US); **Todd Preston Yunker**, Evansville, IL (US); **Kenneth Paul Meissbach**, Lawrence, KS (US)

JP 06293366 10/1994

(73) Assignee: **ConAgra Foods RDM, Inc.**, Omaha, NE (US)

(**) Term: **14 Years**

(21) Appl. No.: **29/351,253**

(22) Filed: **Dec. 2, 2009**

Related U.S. Application Data

(63) Continuation of application No. 29/324,487, filed on Sep. 12, 2008, now Pat. No. Des. 610,903, which is a continuation of application No. 12/040,641, filed on Feb. 29, 2008.

CLAIM

The ornamental design for a container assembly, as shown and described.

DESCRIPTION

FIG. 1 is a perspective view of a container assembly showing our new design.

FIG. 2 is a top plan view of the container assembly of FIG. 1.

FIG. 3 is a bottom plan view of the container assembly of FIG. 1.

FIG. 4 is a left elevation view of the container assembly of FIG. 1.

FIG. 5 is a right elevation view of the container assembly of FIG. 1.

FIG. 6 is a back elevation view of the container assembly of FIG. 1; and,

FIG. 7 is a front elevation view of the container assembly of FIG. 1.

The broken lines illustrate portions of the container assembly which form no part of the claimed design.

1 Claim, 5 Drawing Sheets
